UNITED STATES PATENT OFFICE.

EDWARD BERNARD HESS AND LEWIS CARY MYERS, OF BROOKLYN, NEW YORK,
ASSIGNORS TO ROYAL TYPEWRITER COMPANY, INC., OF NEW YORK, N. Y.

TYPEWRITING MACHINE.

1,417,910.

Specification of Letters Patent. Patented May 30, 1922.

Original application filed January 13, 1921, Serial No. 436,924. Divided and this application filed May 27, 1921, Serial No. 473,172.

To all whom it may concern:

Be it known that we, EDWARD BERNARD HESS and LEWIS CARY MYERS, both citizens of the United States, residing in Brooklyn, 5 county of Kings, city and State of New York, have invented certain new and useful Improvements in Typewriting Machines, of which the following is a specification.

In our application for patent filed January 13, 1921, No. 436,924, of which this application is a division, we have shown a typewriting machine of the Royal type so constructed as to be small, compact and light, but having the essential features of 15 the larger or standard Royal machine, and which is portable and may be sold at a relatively small cost.

That part of the invention herein claimed relates largely to the construction of the 20 frame parts of the machine, but it also includes other features which will be herein-after explained.

We employ sheet metal and drawn stock to a very large extent in the construction of 25 the machine in order to make the mechanism both strong and durable, as well as light and compact. We use the full number of keys in the key board arranged in four banks, as in most standard machines. 30 Mechanism is provided for shifting the platen for upper and lower case printing. Inasmuch as the height of the machine is considerably less than that of the standard Royal machine, the printing point on the 35 platen has been placed considerably above a horizontal line drawn through the axis of the platen, and the type segment has been inclined rearwardly and arranged obliquely with reference to the horizontal plane of 40 the machine in order that the line of print may be properly presented to the eyes of the operator. This involves a new arrangement of the mechanism for connecting the key levers to the type bars in order that 45 the latter may be properly moved from their points of rest to the printing point.

The platen carriage is so mounted and actuated that it moves in a plane oblique to the horizontal plane of the key levers, and the 50 type bars are arranged in a fan-shaped field, i. e., the arc in which the inner ends of the type bars are pivoted is considerably smaller than the arc in which the type carrying ends of the type bars are disposed when at rest.

The construction and arrangement of the 55 mechanism in the new machine is such that all interference of one part with another in the transmission of power from the finger keys to the type bars, which is an essential though a difficult feature in a compact, portable, full-standard key board machine, is avoided.

The key levers are connected with the type bars by flexing connections which exert a tensile strain on the type bars and pull them 60 to the printing point with increasing or accelerated velocity as they approach the printing point. These connections between the type bars and the key levers are made between the finger pieces where power is 65 applied and the fulcra of the levers and said levers are provided with extensions projecting rearwardly from the fulcra which engage a universal bar that controls the movement of the carriage. Thus the key levers, 70 when acting upon the universal bar, are of the first order, and when acting on the type bar mechanism are of the second order.

Inasmuch as the type bars in the new machine are operated by tensile strain only between the key levers and the type bars, and as these connections are made in a novel way, the machine is not impaired in operation as in the case of machines where compression and lateral strain are present in 75 such connections.

Our improvements are illustrated in the accompanying drawings in which:

Figure 1 is a perspective view of the new machine with certain parts not claimed herein omitted.

Figure 2 shows a side elevation of the machine frame.

Figure 3 is a plan view thereof.

Figure 4 shows a longitudinal section of 95 the machine, illustrating parts of the mechanism herein claimed.

Figure 5 is a view looking from the front at the rear portion of the machine frame, and shows how the ends of the frame are 100 joined and covered by a reinforcing tie-plate, which also supports a margin-release lever, a line-lock lever, and a part of the ribbon vibrating mechanism.

Figure 6 shows a portion of the upper 105 part of the machine frame at the front of the machine.

Figure 7 is a perspective view of the as-

sembly frame for the front links and key levers.

Figure 8 is a detail view of said frame.

Figure 9 is a view of the blank from which is formed a support for the front links of the type bar actuated mechanism and a guide for the key levers.

Figure 10 is a perspective view of this support and guide.

Figure 11 is a detail view in perspective, showing how the front links are supported and how the key levers are guided.

The frame base A of the machine is made of thin, light, but stout and strong sheet metal which is blanked out from a single sheet in suitable form to provide the sides, back, front and part of the top portions of the base. Separate front top plates A² are employed and they are secured in place at a⁵. Separate top plates A¹⁰ are attached to the rear portion of the frame. The frame serves as a base support for all of the mechanisms and a casing for portions thereof. The top plates A² serve as a dust-shed for parts of the mechanism. The two ends of the sheet metal frame are brought together at the back of the machine, as indicated in Figure 5, and are connected by a sheet metal tie-plate A' of general T-shape and which is riveted to the opposite ends of the frame as indicated at a'. This plate extends from the bottom of the frame to a plane slightly above the upper edge of the back thereof. This plate in addition to tying together the ends of the frame at the back of the machine serves also to support parts of the mechanism as will be hereinafter described. While a frame thus constructed is strong and quite rigid, we prefer to impart additional strength and rigidity thereto by placing suitable sheet metal reinforcing members a' at the four corners inside the frame. The edges of the sides of the frame are turned inward or flanged as indicated at a² and the top is properly shaped to permit certain parts of the mechanism to project through it.

The tie-plate A', as indicated in Figure 5, supports a margin-release lever L which is pivoted at l to said plate, and it also supports a line-lock lever M pivoted at m to the margin-release lever. A portion of the mechanism for vibrating the ribbon is indicated at M''. This is pivotally mounted at m' on the plate A'. The plate, therefore, serves not only to connect and brace the ends of the sheet metal frame at the rear of the machine, but it serves as a substantial support for the margin release lever, the line-lock lever, and a part of the ribbon vibrating mechanism.

The segment B to which the type bars C are pivoted is of cast metal, and it may be here stated that this member is the only one in the machine which is cast, all other

metal parts being of the lightest possible character. This part is made particularly strong and rigid inasmuch as it sustains a large number of type bars, which must be pivotally mounted in such manner as to be moved with the greatest accuracy and precision toward and from the printing point on the platen. The segment serves to support other parts of the mechanism as will be hereinafter described.

It will be observed that the segment is arranged at an oblique angle to the horizontal, this angle being obtuse to the plane of the key levers as indicated in Figure 4. The segment is formed with a curved rib 80 b which provides a striking surface for the type bars intermediate their ends and insures the impact of the type at the proper point without undue penetration of the material to be printed upon.

The type bars C are thin, light and strong, being made of sheet metal, preferably corrugated, as indicated at c. Their inner ends are disposed in slots b' cut in the lower portion of the segment and they are pivoted 90 to a curved rod or wire b² at the inner ends of the slots.

The type carrying ends of the type bars rest on a support C'. The support C' is suitably cushioned and so disposed as to 95 normally hold the type bars at an obtuse angle to the plane of the segment, but in this case the arc of the support is materially greater than that of the inner bearing points of the segment. In this way the pivoted ends of the bars may be brought close together while the outer ends thereof may be spread so that the type carrying ends of the bars may not interfere. In this way also space is provided in the neighborhood 100 of the segment for accommodating parts of the mechanism.

As shown in Figures 1 to 4 the front part of the machine between the top plates or dust-sheds A² and in front of the support C' is closed by a bridge piece A³ which is attached to the front plates in the manner indicated at a¹⁰. The upper part of this bridge piece is curved in the manner shown and it has a downwardly extending portion a¹¹ (Fig. 4), which reaches to the type bar support H and covers the mechanism immediately in rear of it. In this way the dust-plates A² and the bridge piece A³ serve to protect to a very great extent parts of the mechanism. It will be observed that the type heads are covered by the bridge piece A³ and furthermore that the curved middle portion of this bridge piece is below the top plates A² so that the platen and parts immediately below it are distinctly visible.

It will be also observed that while the mechanism in the rear part of the machine is obliquely arranged the parts in the front 130

portion of the machine, excepting the type bars, are, in general, arranged horizontally. The top plates A^2 are arranged in a true horizontal plane and the ribbon spools K whose shafts extend through the plates A^2 are arranged horizontally somewhat below the line of print and they lie above the plane of the top plates or dust-sheds A^2 . The part A^3 serves to bridge the space between the two plates A^2 at the front of the machine and in this way the mechanism is shielded in a most thorough and efficient way, only such parts as it is necessary or desirable to see being uncovered.

15 The type bars E are normally held on their rest or are returned thereto by individual springs c^2 (Fig. 4) attached to a flange c^3 of the rest and to the type bars near their inner ends in front of and above their pivots. The 20 key board contains the standard number of type keys, viz., 42 arranged in four rows or banks, and it also contains keys for operating the carriage shift, back-space and margin release mechanism. Each of the forty- 25 two key levers E is of the first order being fulcrumed on a common rod e , its front portion being connected to a type bar between the fulcrum and the finger piece, while the rear part of the lever is extended rearwardly 30 from the fulcrum and operates on a universal bar F . Each key lever, therefore, when operating on the universal bar is of the first order, but when operating a type bar it is of the second order inasmuch as at 35 this time the weight is situated between the lever and the fulcrum.

The universal bar is also operated by a space bar S carried by the front ends of levers s pivoted to the rod e and having extensions operating on the universal bar in the same manner as the type key levers. The rear portions of the levers s are connected by a tie bar s' . A stop for the space bar is shown at s^2 .

45 The heels c' of the type bars below and behind their pivots are connected by links g to the rear ends of the short bent links G pivotally mounted on a common pivot rod g' which is supported in a frame of novel construction. Each link G is connected by a link to a corresponding key lever E . The links are made of wire, the ends of which are bent and pass through holes g^3 , c^3 in the links G and levers E respectively. The ends 50 of the links y^1 , y^2 , y^3 , y^4 are bent or hooked as indicated at g^4 , c^4 (Fig. 11) where they engage the levers. In order that the levers may be placed close together to economize space and that the bent ends of the links may 55 not interfere with each other, the links are connected with the levers at different distances from their pivots as shown in Fig. 4.

The rear ends of the key levers move different distances inasmuch as the levers are 60 of different lengths. Therefore, the rear

ends of these levers are inclined at different angles and in such manner as to give to the universal bar the same movement whichever key is operated.

The support H for the front links G is 70 preferably constructed of a single piece of light, strong sheet metal and it is also preferably so constructed as to provide a comb guide for the front portions of the key levers.

Figure 9 shows a sheet metal blank from 75 which the support and guide may be constructed. One part of the blank is provided with two series of parallel slots h' , h^{11} , to accommodate the front ends of the links G while the opposite portion of the blank is 80 formed with a series of parallel slots h^5 to accommodate the key levers. Each end of the blank is formed with a wing or extension h^2 having holes h^3 to receive rivets for securing the support to a frame. The blank is 85 bent on the dotted lines indicated in Fig. 9 to cause the part h^4 of the support to extend rearwardly and then downwardly, parallel with the body of the support. The rod g' to which the front levers are pivoted is disposed between the front and rear portions of the upper part of the support and fits snugly therein. It is supported at its ends and also mid-way between its ends as shown by a loop h^{10} formed from a support H . 90 This rod is held in such manner as to cause the rear portions of the front links to extend through the rear slots h' which are open at their lower ends and through the front slots h^{11} which are closed at both ends. These 95 slots h' , h^{11} are, of course, in line with each other.

The slots h^5 are open at their lower ends to allow the key levers to work through them, and the wings h^2 at opposite ends of the support are bent rearwardly at right angles to the body portion to afford means for securing the support to its frame.

It will be observed that the pivotal connection of the front links with the support 110 is covered and protected by the top of the support, which latter is mounted in a frame consisting of two side pieces J , Fig. 7, each having a flat horizontal base j , a front vertical arm j' and a rear vertical arm j'' . The 115 wings h^2 of the support are riveted to the arms j' at h^3 and the pivot rod g' is supported in the upper ends of the arms. The pivot rod is also centrally supported by a loop h^{10} formed in the support H as shown in 120 Figures 4 and 7. The rear ends of the frame pieces J are connected by a comb guide J' for the key levers. This guide consists of a slotted vertical rear part j'' , a bottom part j^4 and two side portions or wings j^5 . These 125 parts are all made from a single piece of sheet metal bent to shape and secured in place. The frame pieces J are secured to the wings j' at j^3 and each of the wings j^5 is perforated at j^6 to receive the rod e to which 130

the key levers are pivoted. The frame as a whole is secured to the base frame A at a^{10} . The support H and the frame in which it is mounted provide what may be called an assembly frame for the short front links and for the key levers. These may all be mounted in the support and these links and levers thus assembled may be placed in position within the base frame of the machine.

10 The means described for connecting the key levers to the type bars affords a flexing connection between these members and a tensile strain is imparted through the links g from the key levers to the type bars. Furthermore, the connections are such that the types approach the printing point with an accelerated movement which is at first comparatively slow, when the keys are first touched, and they rapidly increase in speed 20 as the depression of the keys continues. Inasmuch as the platen is arranged in an obliquely disposed carriage and the printing point is above the horizontal plane of the axis of the platen the connections between 25 the key levers and the type bars are such as to give the required movement to them.

The arrangement of the type bar operating devices is such as to procure substantially uniform depth of depression and approximately uniform "touch" of all the finger pieces of the key board. The shorter key levers, whose finger pieces x' are in the rear row of the key board are each connected to one of the longer links G by a link y' 30 tending upwardly from the corresponding key lever, the points of connection of the link y' to the link G and to the key lever being such as to afford the desired extent of depression of the finger piece x' of the key 35 lever to throw the corresponding type bar to the printing point. The next longer key levers whose finger pieces x^2 are in the second row from the rear in the key board, are also each connected to a link G by a link y^2 40 but the point of connection of the latter link to the link G is nearer the fixed axis about which the link G moves than is the corresponding link connection of the shortest key lever. The relationship of the parts and 45 leverages is such that the finger pieces x' , x^2 of the two rear rows have the same extent of depression and the same "touch." The next longer levers whose finger pieces x^3 are disposed in the second row from the front of 50 the key board are each connected to one of the shorter front links G as shown in Figure 3 by a link y^3 . The distances from the axes of these shorter links G and from the axes of the corresponding key levers at which the 55 connections of the vertical links are made are such as to afford a depth of depression of the finger pieces, the same as that for the finger pieces x' , x^2 in the two rear rows and also of substantially the same touch.

60 65 Each lever carrying a finger piece x^4 in the front row of the key board is connected to one of the shorter front links by a vertical link y^4 . The connection of the latter link to the front link G is nearer the fixed axis thereof than is the connection between the key levers of the third row and such axis. The finger pieces x^4 of the lower row in the key board have the same extent of depression as the others and substantially the same touch. As the front links G are made alternately long and short, the staggering of the ends of the links with reference to a straight, transverse line affords ample room for the hooks, by which the links g and y' , y^2 , y^3 , y^4 are attached to the links G so that in the operation of the machine one cannot interfere or collide with another. Each front link G is of elbow shape, its lower front end being bent upwards. The point of connection of the type bar link g to the corresponding link G is thus made at a higher point than heretofore. In this way we are enabled to reduce to some extent the height of the machine and parts of the mechanism are made to so co-operate as to effect the full throw of the type bars. Furthermore, the requisite clearances are obtained between moving and stationary parts.

The platen P is mounted in a carriage P' and the ribbon R is led from the spools K through a guide Q. S indicates a device for shifting the ribbon-operating mechanism and S' indicates a device for shifting a bichrome ribbon.

The platen carriage P' is supported on a shift rail W which is moved up and down obliquely. This shift rail is supported by links w pivoted in the machine frame at w' and pivoted to the legs w^2 of the shift rail at w^3 . The rail W is also supported by levers V mounted to move about the axis of the rod V', which is mounted in bearings at opposite sides of the machine. The levers V are pivotally connected with the legs w^2 of the rail W at v . The carriage is raised and lowered for case printing by a rod V^2 connected at v' to one of the levers V. A spring V^3 serves to partially counterbalance the carriage and assists in raising it. The rod V^2 is connected to the lever E² in the manner shown in Figure 4. This lever is pivoted to the assembly frame at e^{10} and is operated by a key in the usual way. The devices E³ shown in the drawings are for the purpose of locking the shift key to hold the carriage raised when so desired. Other mechanism shown in the drawings is more fully shown and described in our co-pending applications.

We claim as our invention:—

1. A typewriting machine in which the platen is obliquely arranged and is provided with mechanism for moving it obliquely for case printing and in which the key-levers and type-bars are arranged substantially

horizontally with dust-sheds horizontally arranged and covering the front part of the machine, the ribbon spools being horizontally arranged below the line of print 5 and above the dust sheds, which are connected by an interposed bridge-piece.

2. A typewriting machine in which the mechanism at the rear is arranged obliquely and the mechanism in the front substantially horizontally and which is provided with two cover plates or dust-sheds and a bridge-piece connecting them at the front which is curved from its outer ends downwardly towards the central longitudinal 15 axis of the machine and which is provided with a downwardly extending portion providing a shield for the front of the machine above the key-board.

3. In a typewriting machine, a base frame 20 made of a single piece of sheet metal bent to form the front, sides and back of the frame and joined at the back, and a tie-plate covering the joint and secured to the frame.

4. In a typewriting machine, a base frame 25 made of sheet metal bent to form the front, sides and back of the base frame and joined at the back, a tie-plate covering the joint and secured to the frame, and margin release mechanism and line lock mechanism 30 supported by the tie-plate.

5. In a typewriting machine, a base frame 35 made of a single piece of sheet metal bent to form the front, sides and back of the frame and joined at the back, and a tie-plate covering the joint and secured to the frame, and carrying margin release mechanism and line lock mechanism.

6. In a typewriting machine, a base frame 40 made of a single piece of sheet metal bent to form the front, sides and back of the frame and joined at the back, a tie-plate covering the joint and secured to the frame, and ribbon vibrating mechanism supported by the tie-plate.

7. In a typewriting machine, type-bars, front links, connections therebetween, key-levers connected with the front links, and a slotted frame in which the front links are mounted and which is formed with an integral comb guide for the key levers.

8. In a typewriting machine, type-bars, front links connecting them, key-levers connected with the front links, a sheet metal frame having front and rear slotted portions 55 through which the front portions of the links extend, and a pivot rod for the links extending between the front and rear portions of the frame.

9. In a typewriting machine, type-bars, 60 front links connected therewith, key-levers connected with the front links, a sheet metal frame having front and rear slotted portions through which the front portions of the links extend, a pivot rod for the links 65 extending between the front and rear por-

tions of the frame, and an integral slotted lower portion providing a comb guide for the key-levers.

10. A frame for supporting and guiding the front links and key-levers of a typewriting machine made of a single piece of sheet metal having slotted upper and lower portions, and wings at the side for securing it to a supporting frame.

11. A frame for supporting and guiding the front links and key-levers of a typewriting machine having front and rear slotted portions at the top adapted to receive the pivot rod of the links and to guide the links, and having a slotted lower portion to provide a guide for the levers.

12. An assembly frame for the front links and key-levers of a typewriting machine, comprising side frame pieces adapted to be secured to the machine frame, and a frame 85 secured to the front ends of the sides having a slotted upper portion for the front links and the pivot rod, and a slotted lower portion to provide a comb guide for the key-levers.

13. An assembly frame for the front links and key-levers of a typewriting machine, comprising side frame pieces adapted to be secured to the machine frame, a frame secured to the front ends of the sides having a slotted upper portion for the front links and the pivot rod, and a slotted lower portion to provide a comb guide for the key-levers, and another comb guide for the key-levers connecting the rear ends of the sides.

14. An assembly frame for the front links and key-levers of a typewriting machine, comprising side frame pieces adapted to be secured to the machine frame, and a frame secured to the front ends of the sides having a slotted upper portion for the front links and a slotted lower portion providing a comb guide for the front portion of the key-levers, and a comb guide for the key-levers connecting the rear ends of the sides 110 and supporting the pivot rod of the key-levers.

15. An assembly frame for the front links and key-levers of a typewriting machine, comprising side pieces made of sheet metal 115 having front wings and rear wings, a frame secured to the front wings of the sides having a slotted portion to receive the front links and a slotted portion to provide a comb guide for the key-levers, and another comb 120 guide for the key-levers attached to the wings at the rear ends of the frame.

16. An assembly frame for the front links and key-levers of a typewriting machine, comprising an integral slotted support and a comb guide for the front links and a comb guide for the key-levers, and a rear comb guide for the key-levers connected with the front support and supporting the rear ends of the key-levers.

17. An assembly frame for the front links and key-levers of a typewriting machine, comprising an integral slotted support and guide for the front links and a comb guide for the key-levers, and a rear comb guide for the key-levers connected with the front support and containing the pivot rod for the key-levers, and detachable connections between said assembly frame and base frame

of the machine whereby the front links, 10 their pivot rod, the key-levers and their pivot rod may be removed bodily and altogether from the machine and replaced in such condition.

In testimony whereof, we have hereunto 15 subscribed our names.

EDWARD BERNARD HESS.
LEWIS CARY MYERS.
